UNITED STATES PATENT OFFICE.

EMIL F. LINKE, OF HARTFORD, CONNECTICUT, ASSIGNOR TO THE THORNE
TYPE-SETTING MACHINE COMPANY, OF JERSEY CITY, NEW JERSEY.

TYPE-JUSTIFYING APPARATUS.

SPECIFICATION forming part of Letters Patent No. 626,914, dated June 13, 1899.

Application filed July 20, 1893. Serial No. 481,020. (No model.)

To all whom it may concern:

Be it known that I, EMIL F. LINKE, a citizen of the United States, residing at Hartford, county of Hartford, and State of Connecticut, have invented certain new and useful Improvements in Type-Justifying Apparatus, fully described and represented in the following specification and the accompanying drawings, forming a part of the same.

This invention relates to type-justifying apparatus of the class adapted especially for use in connection with those type-setting machines in which the matter is received in the form of a continuous line, which line is afterward divided by hand into short lines of suitable lengths for a column or page, justified, and added to a column upon a printer's galley.

A type-setting machine of the class referred to is shown and described in United States Letters Patent Nos. 232,157, 283,934, 372,186, and 372,187, and justifying apparatus of this class in United States Letters Patent Nos. 387,546, 388,088, and 467,335, and the present invention includes improvements upon the justifying apparatus of these patents, these improvements, however, being of general application in justifying and similar apparatus.

The invention includes also various constructions and combinations of parts, some of which are applicable in type setting and distributing apparatus other than justifying apparatus, all of which constructions and combinations will be particularly described in the following specification and pointed out in the claims.

For a full understanding of the invention a detailed description of an apparatus embodying the same in the preferred form will now be given, reference being had to the accompanying drawings, forming a part of this specification, in which—

Figure 1 is a side elevation of a justifying apparatus of the preferred form embodying my invention. Fig. 2 is a plan view of the same. Fig. 3 is a cross-section on the line 3 of Fig. 1 with the galley removed. Fig. 4 is a cross-section on the line 4 of Fig. 1. Figs. 5 and 6 are cross-sections of the space-packing mechanism, showing the parts in different positions.

Referring to said drawings, A is the galley for holding the lines of justified type in column; B, the table containing the guideway over which the continuous line of type *x* is fed to be justified; C, the column-packer by which the justified lines are packed in the galley A; D, the rule, against which the type are justified; E, a chute into which spaces removed from the line are thrown; F, a funnel receiving the spaces from the chute and from which they are delivered through a guideway G to a space-packer I, by which the spaces *y* are packed in line in the space-case H.

The galley A is supported at one end upon the head of the machine K, which consists in the form shown of a vertical bracket on the frame, and the galley inclines downward and is supported at its rear end upon an arm 10 on the head K, resting against a shoulder 1 on said arm and being held by a pivoted catch 11, spring-pressed to hold the galley by a spring 12. In the galley-holding position, as shown in the figures, this catch laps over the rear end of the galley and holds it down upon the arm 10, securing the galley in place, and by rocking the catch backward against spring 12 the galley is released.

The column-packer C is carried by a rock-shaft 13, mounted in the head and provided with a crank-arm 14, to which is pivotally connected an eccentric-rod 15, carried by an eccentric-sleeve 16, actuated by an eccentric 17, loose on the shaft L and carrying a stop-disk 18 concentric with the shaft. The shaft L is driven, preferably, by a pulley and belt M, for a purpose presently to be described, and carries a ratchet-disk 19, having notches 2, and upon the eccentric 17 is pivoted a pawl 3, spring-pressed toward said notches, so as to engage therein when not held against the tension of the spring, the pawl being provided with a trip-arm 4, by which the pawl may be thrown and held out of the notches against the spring. This trip-arm 4 is engaged by a stop 20, forming the end of a trip-lever N, pivoted on the head of the machine and provided on its upwardly-extending arm with a finger-piece 21 in position for convenient use by the operator. The stop-disk 18 is provided with a single notch 5, engaged by a spring-

pressed pawl 22, pivoted on the frame of the machine, this stop-disk and notch serving to prevent backward movement of the eccentric when stopped by trip-lever N, and the stopping-surface of the notch 5 preferably being inclined rearward, as shown, for a purpose presently to be described.

For the purpose of operating the rule in proper relation to the packer the following construction is preferably used: The column-packer shaft 13 carries a segmental gear 23, which engages a rack 24, sliding in the head K, this rack being attached to the rule D, so that as the shaft 13 is rocked for the operation of the packer the rule is raised and lowered in proper time. The chute E for the spaces is mounted in convenient position for the operator and preferably, as shown, just opposite the galley and with its upper end opening between the arms of the packer. The chute is curved transversely to the machine, as shown in Fig. 4, only for compactness and of course may be straight. The spaces are delivered from the chute E into a funnel F, which is set into an opening in a bracket 25 and has its upper edge under a lip 6, so as not to interfere with the type. Thus the funnel is free to be removed from the bracket, and the chute is so arranged relatively to the funnel that the latter may be removed without disturbing the former, this construction enabling the funnel to be readily removed and restored to place for clearing it in case of its being clogged by the spaces. Below the vertical funnel F and bracket 25 is the inclined guideway G, which is formed with a V-shaped channel having a square bottom, so that the type are turned edgewise and run down the guideway at the bottom of the channel on their edges. At the lower end of the guideway G the type are received by the packer I, which, as shown, consists of a disk provided with cams, each extending through a half-circumference and terminating abruptly in a shoulder upon which the space is received from the guideway G, the cam-surface of the disk operating to press the space into line as the space is lowered by the rotation of the disk carrying the shoulder downward. The packer I is shown as carried by a shaft 26, driven by a pulley 27 and belt.

The operation of the construction will be understood from a brief description. In Fig. 1 the parts are shown in their normal position, with the packer C withdrawn and the rule D raised above the galley for the justifying of a line received from the table B. In this position of the parts the trip-lever N is in its rear position, with the end 20 engaging the trip-arm 4 of the pawl 3 and holding the pawl out of engagement with the notches 2 on the disk 19, so that the shaft is free to rotate independently of the eccentric and the eccentric is held in position by the lever N and the pawl 22. When the line is justified and ready to be transferred to the galley, the trip-lever N is rocked toward the packer by

the operator, thus throwing the end 20 upward and out of engagement with trip-arm 4, and the spring then presses the pawl 3 downward into position to engage the next one of the notches 2, which is brought opposite it by rotation of the shaft L. As the pawl takes into notch 2 the eccentric 17 is rotated with the shaft and through the eccentric-sleeve 16, eccentric-arm 15, and crank-arm 14 rocks the shaft 13 and throws the column-packer up against the line of type, so as to carry the latter into the galley and press the column downward in the galley the distance of one line, the rule D having meanwhile been withdrawn on the rotation of the shaft 13 by the segment 23 and rack 24. The eccentric is carried with the shaft for one rotation only, the trip-arm 4 of the pawl 3 coming against the end 20 of the lever N at the end of the rotation, the trip-lever having meanwhile been returned by its weight or a spring when the pawl 3 is thrown out of the notch 2, and the shaft continues its rotation, while the eccentric 17 stops. As the pawl may not be thrown out of the eccentric sufficiently to prevent its drag upon the wheel 19 and engagement with the edge of the notches, the raising of the pawl out of engagement with the wheel 19 is assured by the stop-pawl 22, which not only prevents the rebound of the eccentric, but also by engaging the inclined stopping-surface of the notch 5 throws the eccentric forward slightly but sufficiently to assure the proper positioning of the pawl 3. As the spaces are removed they are thrown into the chute E, which is conveniently placed and pass then through the funnel F to the guideway G and packer I, by which they are packed in line in the space-case II, as previously described.

It will be seen that the invention provides a very simple and convenient construction of space-packing mechanism which may readily be cleared in case of blockage and is located and combined with the column-packing mechanism so as to be most convenient for the operator, the two constructions of justifying and space-packing mechanism together producing a justifying apparatus capable of operation at a very high rate of speed.

It will be understood that many modifications may be made in the form and arrangement of the devices for operating the column-packer and rule without departing from the invention, and I am not to be limited to the specific construction shown. It will also be understood that the column-packing and space-case mechanism may be used independently and each with other constructions of the other mechanism; but the invention consists in part of the combination of the two mechanisms, by which a simple, compact, and efficient justifying apparatus is provided.

What is claimed is—

1. The combination with the galley, column-packer and rule of a type-justifying apparatus, of connections between the column-

- 5 packer and the rule to cause them to have a relative positive movement, a power-driven rotary member, a second rotary member by which the column-packer and rule are positively actuated in both directions of their movements, a clutch for connecting said rotary members, and means controlled by the operator for operating said clutch, substantially as described.
- 10 5. 2. The combination with the galley, column-packer and rule of a type-justifying apparatus, of a power-driven rotary member, a second rotary member by which the column-packer and rule are positively actuated in both directions of their movements, a clutch for connecting said rotary members and means for automatically operating said clutch to disconnect the members, and means controlled by the operator for operating said clutch to connect the members, substantially as described.
- 15 3. The combination with the galley, column-packer and rule of a type-justifying apparatus, of connections between the column-packer and the rule to cause them to have a relative positive movement, a power-driven rotary member, a second rotary member by which the column-packer and rule are positively actuated in both directions of their movements, and means for connecting said rotary members at the will of the operator and automatically disconnecting said members after the column-packer and rule have been actuated and returned to their normal positions, substantially as described.
- 20 4. The combination with the column-packer, of the shaft L, an eccentric loose on said shaft and having a crank connection with the column-packer, ratchet-wheel 19 rotating with shaft L, pawl 3 on the eccentric having stop-arm 4, hand-lever N carrying stop 20 engaging the stop-arm 4 in its normal position, stop-disk 18, and stop-pawl 22, substantially as described.
- 25 5. The combination with the column-packer, of the shaft L, an eccentric loose on said shaft and having a crank connection with the column-packer, ratchet-wheel 19 rotating with shaft L, pawl 3 on the eccentric having stop-
- 50 arm 4, hand-lever N carrying stop 20 engaging the stop-arm 4 in its normal position, stop-disk 18, having backwardly-inclined notch 5, and stop-pawl 22 engaging said notch 5, substantially as described.
- 55 6. The combination with the pivoted column-packer and rule, of gear 23 and rack 24 connecting said column-packer and rule, shaft L, eccentric 16 loose on said shaft and having a crank connection with the column-packer, ratchet-disk 19 rotating with shaft L, pawl 3 carried by the eccentric and having stop-arm 4, hand-lever N carrying stop 20 normally engaging the stop-arm, stop-disk 18 on the eccentric, and stop-pawl 22, substantially as described.
- 60 7. The combination with a type-justifying apparatus and its galley and column-packer, of a space-packing mechanism, and a space-chute extending from a point at and below the open end of the galley of the type-justifying apparatus to the space-packing mechanism, substantially as described.
- 65 8. The combination with the space-case H and a space-packer, of a guideway to said packer, removable funnel F above said guideway, and chute E above said funnel, substantially as described.
- 70 9. The combination with the galley and column-packer of a type-justifying apparatus, of a space-case H and a space-packer, inclined guideway G, detachable funnel F, and chute E extending from a point at or near the open end of the galley to the funnel, substantially as described.
- 75 10. The combination with the inclined space-case H, of the inclined guideway G, cam-packer I operating on an incline at the foot of the guideway, detachable funnel F above the guideway, and chute E above said funnel, substantially as described.
- 80 In testimony whereof I have hereunto set my hand in the presence of two subscribing witnesses.
